AIRFOIL CABINET FOR A TRUCK

Leo G. Arnold, Jr., 801 St. Louis St.,
Joplin, Mo. 63031

Filed Oct. 12, 1972, Ser. No. 297,075

Term of patent 14 years

Int. Cl. D12—16

U.S. Cl. D14—6 A

FIG. 1 is a rear elevational view of an airfoil cabinet for a truck showing my new design;

FIG. 2 is a side elevational view of the airfoil cabinet, the opposite side being a mirror image of the view shown in FIG. 2;

FIG. 3 is a top plan view of the airfoil cabinet;

FIG. 4 is a bottom plan view of the airfoil cabinet;

FIG. 5 is a front elevational view of the airfoil cabinet; and

FIG. 6 is a side elevational view of the airfoil cabinet installed on a truck, shown in broken lines with a trailer to indicate the environment in which my invention is used it being understood that the broken lines are for illustrative purposes only.

I claim:

The ornamental design for an airfoil cabinet for a truck, as shown and described.
